UNITED STATES PATENT OFFICE.

JOHN CUTHERBERT, OF CHICAGO, ILLINOIS.

WIRE COILING AND BINDING CLAMP.

1,243,716.

Specification of Letters Patent. Patented Oct. 23, 1917.

Application filed February 24, 1916. Serial No. 80,114.

To all whom it may concern:

Be it known that I, JOHN CUTHERBERT, a citizen of the United States, residing at Chicago, in the county of Cook and State of Illinois, have invented certain new and useful Improvements in Wire Coiling and Binding Clamps, of which the following is a specification.

My invention relates to wire coiling and binding clamps, which may serve as terminals for electric translating devices, and the like.

One of the objects of my invention is to provide improved means for coiling a wire around the shank of a screw-threaded member, such for instance as a screw, stud or the like, and to thereafter clamp and hold the wire end within a prescribed annular zone to prevent any lateral or radial movement thereof away from its clamping members or any undesirable movement of the wire toward the threaded shank or stud when said means is being rotated to coil and clamp the wire.

In my Patent No. 1,166,114 dated December 28th, 1915, I have disclosed one form of the device in which the relatively stationary member is shown to be provided with a stop, such as a slot or stud for holding the wire to be coiled around the shank of the clamping means, to prevent it from moving laterally or radially away from the shank and from under the rotating clamping member during clamping operation, and in my application Serial No. 64,635 filed December 2, 1915, I have disclosed a structure wherein the stationary clamping member is provided with a recess within which to receive the screw head and to prevent lateral displacement of the wire from under the screw head.

In my present invention I have provided means for bending the wire on a longer radius than before and a guide and guard whereby the end of the wire is bent into an eye of predetermined size and held in a plane concentric with the shank and prevented from moving laterally from between the clamping members.

Other, further and more specific objects of my invention will become readily apparent, to persons skilled in the art, from a consideration of the following description when taken in conjunction with the drawings, wherein:

Figure 1 is a central, vertical section of

my improved wire coiling and clamping device, showing the wire inserted in place prior to the coiling and clamping operation.

Fig. 2 is a plan view of the screw head, as shown in Fig. 1, with the wire engaging the shoulder in the head.

Fig. 3 is a transverse section taken on line 3—3 of Fig. 1 showing the under side of the screw head.

Fig. 4 is a section, similar to Fig. 1, showing the wire coiled and clamped.

Fig. 5 is a section taken on line 5—5 of Fig. 2.

Fig. 6 is a section taken on line 6—6 of Fig. 4, showing the clamping screw head removed.

Fig. 7 is a section, similar to Figs. 1 and 4, showing a modification.

Fig. 8 is another modification showing a part of the screw head cut entirely away to provide a wire engaging shoulder, instead of the equivalent slot, as shown in Fig. 2.

In all the views the same reference characters are employed to indicate similar parts.

10 is a base, or relatively stationary 80 clamping member of the device, screw threaded for the screw shank 11 of the screw 12. The base is provided with a perforation 13 through which to pass the wire 14; the wire is shown to enter the perforation 13, in the base 10, at an angle to the perpendicular and to then extend in a vertical direction under the screw head 15. The perforation 13 could as well extend parallel with the shank 11 the entire distance 90 through the base, if desired. It is advantageous, many times, to have the perforation laterally deflected, as shown, as in panel-board blocks or other such fixtures.

The screw head is provided, on its under 95 surface, with an annular wire guard and guiding groove 16, shown more clearly in Fig. 3, inter-spaced between an annular shoulder 17, near the shank of the screw, and an outlying annular shoulder 18, radially beyond the groove. Between these shoulders and within the groove the wire is guided while being coiled and within which the coiled end or eye of the wire is to be retained.

The head of the screw is perforated with an elongated slot, as at 19, or a part of the screw head may be entirely cut away as at 19' and removed to provide wire engaging shoulders 20, 20', respectively. The perfo- 110

ration or notch terminates in the underside of the screw head, in the annular groove 16, as shown in Fig. 3. The shoulders 20, 20' are cut back, as at 21, as shown in Fig. 5 to provide an angularly disposed rearwardly inclined shoulder. One of the objects of inclining the shoulder 20—20' is to engage the wire 14 at a point near the top surface of the head of the screw, or as far away from the base 10, as may be, so as to give the wire a relatively longer bend from perpendicular to a horizontal plane, to prevent shearing of the wire when the screw is turned.

Another object of under cutting the shoulder, as at 21, to incline it is to cause the wire to be correspondingly inclined so as to present a relatively larger contacting surface of the shoulder with the wire to more easily bend the wire into an annular eye, without cutting or abrading it. The inclined surface also serves as a guide for directing the wire into the opening before the shoulder, from the perforation below.

The bottom part 21, of the shoulder 20, leads into the annular wire guiding groove 16 made in the underside of the head of the screw, so as to bend an eye in the wire of diameter predetermined by the size of the groove and to prevent the wire from being drawn into too close or intimate contact with the threaded shank 11 of the screw during coiling operation. After the wire enters the groove 16, as the screw is turned clockwise, the shoulder 17 maintains the wire within the groove and determines the size of the eye to be formed in the end of the wire and the annular shoulder 18 prevents the wire eye from leaving the groove.

In the use of the device the wire 14 is inserted in the perforation 13, provided in the base 10, as shown in Fig. 1, until the end 14' of the wire extends above the head of the screw sufficiently to provide a suitable length of wire of which to make the eye, as shown in Fig. 6. The screw is then rotated, whereupon the upper portion of the shoulder 20 near the top of the screw head will be brought into contact with the vertically extending wire, and further rotation of the screw will bend it forwardly so as to substantially correspond with the inclination of the shoulder, as at 21. As the screw is further turned the groove 16 will over-ride the curved portion of the wire 14 and guide the wire, while the shoulder 17, a result of the groove, will prevent the wire from hugging too closely to the shank 11 of the screw. After the screw has been rotated one complete revolution, the wire will thereby have been bent into an eye, the diameter of which is determined by the groove 16.

The screw may now be further turned until the head 15 clamps the wire eye 14' in the groove 16, in contact with the base 10. When this is done, as shown in Figs. 4 and

7, the wire cannot escape from under the head of the screw being encompassed by shoulder 18. A groove 16', substantially the same as the groove 16 in the head of the screw, may be made in the base 10, within which to receive the eye of the wire or a more shallow groove may be made in each of the clamping members, the head and in the base, as shown in Fig. 7, between which to retain the eye of the wire.

In forming the eye in the end of the wire, in the manner heretofore described, the resiliency of the wire will, to some extent, retain the screw in the position in which it has been placed in the act of clamping the wire by the friction thus produced serving to prevent its being rotated in the opposite direction to loosen the clamping screw.

To prevent the wire 14 from making too sharp a curve or turn, at the upper termination of the perforation 13, it is well to counter sink the terminal of said perforation, as shown at 25, in Figs. 4 and 6, thereby chamfering the edge of the perforation and removing the sharp corners.

While I have herein shown a wire 14, and referred to it as such, it is not necessarily a solid wire, as a stranded cable may be operated upon in the same manner and clamped by the same instrumentalities as the wire, and while I have shown the preferred form of my invention it will be evident to persons skilled in the art, that it is susceptible of many modifications, not necessary to be shown, but within the scope of the appended claims.

Having described my invention, what I claim is:

1. A wire coiling and binding clamp comprising a relatively stationary clamping member and a rotatable screw-threaded clamping member, the latter having a part to engage a wire to bend it into an eye about a shank around the axis of which said members are relatively rotatable and a wire guide for determining the size of the eye.

2. A wire coiling and binding clamp comprising a relatively stationary clamping member and a rotatable screw threaded clamping member, the latter having a part to engage the wire to bend it into an eye, about the shank around the axis of which said members are relatively rotatable and having a groove substantially concentric with said shank, within which to include the eye of the wire when formed.

3. A wire coiling and binding clamp comprising a relatively stationary clamping member and a rotatable screw threaded clamping member, the latter having a part to engage the wire to bend it into an eye, about the shank around the axis of which said members are relatively rotatable, and two spaced apart annular shoulders with a groove therebetween on either of said con-

fronting clamping members, within which to contain said eye when said clamping members are in clamping positions.

4. A wire coiling and bending clamp comprising two confronting clamping members relatively rotatable around a common axis, one of said members having a perforation for insertion of a wire within the area overlain by the other clamping member, the latter member having a part to engage the wire to form an eye when said members are relatively rotated and having a groove within the circumferential path described by said wire engaging part, within which to retain said eye between said members.

5. A wire coiling and binding clamp comprising two confronting clamping members relatively rotatable around a common axis, one of said members having a perforation for insertion of a wire within the area overlain by the other clamping member, the latter member having a rearwardly inclined shoulder to engage the wire to bend it forwardly prior to forming an eye therein, when said members are relatively rotated, and having an annular groove, in which said shoulder terminates, within the circumferential path described by said shoulder, within which to retain said eye, between said members.

6. A wire coiling and binding clamp comprising a stationary member and a screw, said screw having in the under surface of its head an annular groove and a rearwardly inclined wire-engaging shoulder terminating in said groove, the stationary member having a perforation for insertion of a wire in front of said shoulder and in the vertical plane in which said groove is located.

40 7. A wire coiling and binding clamp comprising a stationary member and a screw, said screw having in the under surface of its head an annular groove and a perforation

passing through its head to provide a wire-engaging shoulder terminating in said groove, the stationary member having a perforation for insertion of the wire in front of said shoulder, substantially registering with the shoulder provided on the screw head, whereby to bend an eye in the end of the wire, and to retain said wire under said screw head.

8. A wire coiling and binding clamp comprising two confronting clamping members relatively rotatable around a common axis, one of said members having a perforation for insertion of a wire within the area overlain by the other clamping member, the latter having a part to engage the wire to form an eye when said members are relatively rotated and one of said members having a recess within said area, in which to retain said eye when formed.

9. A wire coiling and clamping member comprising a screw having a part to engage a wire to coil it around its shank and having a wire-receiving recess in the under side of the screw head to retain the coil.

10. A wire coiling and binding clamp comprising two confronting clamping members relatively rotatable about a common axis, one of said members having a perforation, for insertion of the wire, within the area overlain by the other clamping member, the latter member having a rearwardly inclined shoulder to engage the wire to bend it forwardly prior to forming an eye therein by the relative rotation of said members.

In testimony whereof I hereunto set my hand in the presence of two subscribing witnesses.

JOHN CUTHBERT.
